BICYCLE PEDAL

Harry Golden, 250 W. 57th St., New York, N.Y.

Filed July 30, 1963, Ser. No. 76,038

Term of patent 7 years

(Cl. D90—14)

FIGURE 1 is a top plan view of a bicycle pedal embodying my new design, with the portions shown in broken lines being included for illustrative purposes only; FIGURE 2 is an outer end elevational view of the same; FIGURE 3 is a front elevational view thereof; and FIGURE 4 is a perspective view showing the sides opposite those shown in FIGURES 1, 2 and 3.

I claim:

The ornamental design for a bicycle pedal, as shown.
